Primary Examiner — Keli L Hill*Assistant Examiner* — Harold E Blackwell, II(74) *Attorney, Agent, or Firm* — Grace J. Fishel(57) **CLAIM**

The ornamental design for a gutter support bracket assembly as shown and described.

DESCRIPTION

FIG. 1 is a side view of a gutter support bracket assembly showing my new design in use on a gutter;

FIG. 2 is a perspective view of a gutter bracket portion thereof;

FIG. 3 is a side view thereof;

FIG. 4 is a top view of the thereof;

FIG. 5 is a bottom view thereof;

FIG. 6 is a front view thereof;

FIG. 7 is a rear view thereof;

FIG. 8 is a perspective view of a roof strap portion thereof;

FIG. 9 is a side view thereof;

FIG. 10 is a rear view thereof; and,

FIG. 11 is a front view thereof.

The gutter, roof, soffit and threaded fasteners shown in broken lines in FIG. 1 denote the nature and environment use of the design and are not part of the design.
